(57) **CLAIM**

The ornamental design for a storage bucket, as shown and described.

DESCRIPTION

FIG. 1 is a perspective view of a storage bucket showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top plan view thereof;

FIG. 8 is bottom plan view thereof;

FIG. 9 is an exploded perspective view thereof, shown in another configuration and separating the base from the storage bucket;

FIG. 10 is another perspective view thereof, shown in a folded state; and,

FIG. 11 is another perspective view thereof, shown with the base placed in the folded storage bucket.

The broken lines illustrate portions of the storage bucket that form no part of the claimed design.

1 Claim, 11 Drawing Sheets
